(57) **CLAIM**

The ornamental design for a desktop computer, as shown and described.

DESCRIPTION

FIG. 1 is a front perspective view of a desktop computer with pink portions, showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a bottom perspective view thereof; and,

FIG. 9 is an enlarged partial view of portion 9 taken from FIG. 7.

The dashed broken lines in the figures depict portions of the desktop computer that form no part of the claimed design. The dot-dash lines in the figures depict the boundaries of the enlarged views and form no part of the claimed design.

The drawings are lined for color. The vertical line shading in the figures represents elements that are pink in color, specifically Pantone 12-2904.
